UNITED STATES PATENT OFFICE

2,204,566

BUILDING FRAME STRUCTURE

Henry W. Buelow, Detroit, Mich.

Application October 3, 1938, Serial No. 233,014

5 Claims. (Cl. 189—36)

The present invention relates to building frame structures, and particularly to the provisions of improved bridging or like members adapted to form a supporting or reinforcing connection between adjacent structural members; and is a continuation in part of applicant's co-pending application, Serial No. 41,364, filed September 20, 1935.

A principal object of the present invention is to provide a metal framing structure having improved bridging and supporting connections between the structural members thereof, and an improved method of erecting the same.

Further objects of the present invention are to provide a bridging or supporting connection between a pair of spaced structural members, wherein the structural members are provided with expansible flanges, and wherein the bridging or supporting member is formed at its ends to interlock with such flanges, whereby a nail or other fastener may be driven through such ends into the flanges to expand the same into gripping engagement with such ends.

With the above as well as other and more detailed objects in view, which appear in the following description, and in the appended claims, preferred but illustrative embodiments of the invention are shown in the accompanying drawing, throughout the several views of which corresponding reference characters are used to designate corresponding parts, and in which:

Figure 1 is a view in perspective of the improved bridging arrangement of the present invention;

Fig. 2 is a detailed view of an individual bridging member;

Fig. 3 is a fragmentary view of a modified bridging arrangement;

Fig. 4 is a detailed view of the bridging element shown in Fig. 3; and

Fig. 5 is a view in perspective of a trimmer joist arrangement embodying the invention.

In accordance with the invention disclosed in the above identified parent application, Serial No. 41,364, a complete framing structure, for homes, as well as for a wide variety of other structures, may comprise a relatively few standard shapes. These structural shapes may be erected through use of a relatively few, economically formed attaching elements.

The main structural members, which may be of I, T, or channel section, are preferably of the type disclosed in Patent No. 1,900,541, granted March 7, 1933, on application Serial No. 548,134, filed July 1, 1931, by the present applicant and

George Buelow. As described and claimed in that patent, these members, which may be formed of either single or double web construction, are characterized as being formed of two angle or channel members arranged in back-to-back relation and rigidly secured together with the opposed and adjacent faces in spaced relation. These opposed and adjacent faces are corrugated in the direction of their length, the corrugations of one being complementary to the corrugations of the other. Those portions of members which are opposed and adjacent each other are of rigid and self-supporting character and they are so spaced with respect to each other as to form between them a sinuous slot of such character that when a nail or similar fastener of the character intended for use therewith is driven into the slot between the members in a direction transverse to the slot, the nail or fastener is caused to bend and to approximately follow the sinuosity of the slot to thereby positively fix the nail or fastener in position with respect to the members. With this construction, a substantial portion of the erection by simply nailing parts together in the manner now customary in the erection of wooden frame structures.

The improvements of the present application are specifically directed to improved bridging and trimmer joist arrangements, characterized, in one sense, in that bridging of trimmer joist elements are provided at their ends with parts adapted to interlock with the flanges of associated joists or equivalent members, whereby a nail or other fastener may be driven through such ends into the expansible flanges of the joists, so as to expand the same into gripping engagement with the bridging element or trimmer joist. The improvements to which the present application is directed are, however, susceptible of a more general use than that indicated and the illustration of such improvements in connection with bridging and trimmer joist arrangements is not, therefore, to be considered in a limiting sense.

Referring to Fig. 1, it will be understood that members 10 may represent floor joists or other structural members, and that a plurality of bridging members 12, preferably arranged in pairs, are distributed along the length of members 10 to reinforce them and hold them in predetermined spaced relation to each other. The members 10 are of I section, and embody the construction claimed in the aforesaid Patent No. 1,900,541.

Referring to Fig. 2, a preferred bridging member 12 is formed of channel section with the ends oppositely notched at 14. Each notch 14 is

- formed by cutting a rectangular section from one leg and correspondingly cutting the channel web. The inner face of each notch 14 is provided with an inwardly extruding notch 16 of generally V form, for a purpose mentioned later. Each flange end portion not notched is pierced at 19 opposite the corresponding notch to permit nailing of the bridging member to an associated member such as 10.
- 10 It will be understood that the spacing between the bases of the notches 16 is substantially equal to but slightly less than the spacing between the marginal edge of an upper flange on one of the members 10 and the marginal edge of the lower flange of a companion member 10. It will further be understood that the spacing between the notch edges 14a and 14b of each notch 14 is slightly in excess of the width of the joist flanges. With this relation, a bridging member 12 may be 20 preliminarily positioned with respect to the two joists 10, a part of a flange of each joist being received in the corresponding notch 16. This position of the bridging member 12 may be effected by first inserting the flange of one joist into one 25 notch 16, swinging the other end of the bridging member to a position at an angle to the normal disposition thereof, sufficient to permit the flange of the other joist to be inserted in the notch 14 at the corresponding end, and thereafter re- 30 swinging the bridging member to a position at right angles to the two joists.

With the parts in this position, the end portions may be bent along the lines 20 and 22, bringing the portions 18 parallel with and in 35 abutting relation to the flange surfaces. The positioning is completed by bending the extremities 24 of the end sections around behind the joist flanges along the lines 22.

The assembly is completed by driving nails 26 40 or other fastening elements through the openings 19 therein and into the slots 10a formed in each joint flange. This operation, as described in the above paragraph, expands the flanges so that the opposite marginal edges 45 thereof bear solidly against the bases of the corresponding notches 16 and against the opposite faces 14a of the corresponding notch 14. The insertion of the nail or other fastener also deforms the same, due to the curvature of the nailing groove in joist 10, thus firmly securing the nail or other fastener in place. The resultant 50 assembly is therefore one which can very readily and economically be erected and which at the same time is thoroughly rigid and effective.

55 In the modified embodiment of the invention shown in Figs. 3 and 4, the bridging element 30 is of generally channel shape, the web and one flange whereof are cut away at each end, leaving the remaining flange portions 32 and 34 extending beyond the ends of the intermediate 60 channel portion. The bridging element 30 may be preliminarily positioned with respect to its associated joists or other members 10 in the manner described above with reference to the bridging member 30. After such preliminary positioning, the extreme end portion 34 of each flange portion 32 is bent down and around beneath the corresponding flange portion 10' of the associated joist. It will be understood also 65 that the opposite marginal flange edge lies closely adjacent the abutment 36 constituted by the end of the web of the bridging member. The assembly is completed as described above by passing a nail or other fastener 38 through each 70 flange portion 32 into the joist nailing groove,

which action expands the flange into tight gripping engagement with the bridging member.

It will be understood that it is frequently desirable to form a connection between the adjacent joists or other structural members which serves as a support for a partition or the like. An example of such an instance is in connection with non-bearing partitions which may lie parallel to but between two adjacent joists. In such instances, as well as others, the improved trimmer 10 joist of the present invention may be used to advantage.

Referring particularly to Fig. 5, trimmer joist 40 comprises a T section, the ends 42 of which are deformed to provide U-shaped members 15 which rest upon adjoining joists or other members 44. As will be understood, the web 44 is cut away throughout each U-shaped portion, as indicated at 48. The U-shaped portions 42 are knocked up from the main level of the flange 50 20 to an extent substantially equal to the thickness of the flanges of joists 44, so that after erection of the trimmer joists the central section of the flange 50 is of the same level as the tops of the flanges of the main joist 44. The ends 52 25 of the U-shaped sections 42 are turned down and, after the trimmer joist is in place, the extreme end portions are turned under the flanges of the main joists 44.

As in the case of the bridging members, the end portions 42 of each trimmer joist 40 are provided with nailing openings, through which fasteners such as 54 may be passed to expand the flanges of the joists 44 into gripping engagement with the lateral sides of the U-shaped portions 42, thus firmly locking the trimmer joist in place with respect to the joists 44.

Although only specific embodiments of the invention have been described in detail, it will be appreciated that various modifications in the form and arrangement of parts may be made within the spirit and scope thereof.

What is claimed is:

1. In a structural assembly, a connection between a pair of spaced members each having an expandable flange, comprising a unitary member having an intermediate portion formed to extend between said members and having end portions integral with said intermediate portion and disposed to interlock with said flanges respectively, said end portions being dimensioned to wedge on said flanges when the latter are expanded, and a fastening element operatively associated with each said flange so as to effect said expansion of the corresponding flange.

2. In a structural assembly, a connection between a pair of spaced members at least one whereof has an expandable flange, comprising a member having an intermediate portion formed to extend between said members and having at least one end portion constituted by an abutment and a bendable tongue, said tongue being bent around said flange so that when said flange is expanded it is wedged between said bent tongue and said abutment, and a fastening element operatively associated with said flange so as to effect said expansion of said flange.

3. In a structural assembly, a connection between a pair of spaced structural members each having expandable flanges; comprising a member having an intermediate portion disposed to extend diagonally between said flanges, and having end portions disposed to interlock with said flanges, said end portions being disposed to wedge on said flanges when the latter are expanded,

and a fastening element operatively associated with said flange so as to effect said expansion of said flange.

4. In a frame structure, a connection between two spaced members each having an expandible flange comprising an element having a flat central section of predetermined thickness and end sections of corresponding thickness, said end sections being knocked up from said central section substantially the thickness of said end sections, and said end sections being disposed to interlock with said flanges when the latter are expanded, and a fastening element operatively associated with each flange to expand it into interlocked relation to the corresponding end section.

5. In a structural assembly, a connection be-

tween a pair of spaced members each having an expandible flange and disposed so that a member extending diagonally between them overlies said flanges, comprising a bridging member extending diagonally between said spaced members, said bridging member having end portions each constituted by an abutment and a bendable tongue, each said tongue being bent around the corresponding flange so that when said corresponding flange is expanded it is wedged between the associated tongue and abutment, and a fastening element passed through each end portion into the corresponding flange so as to effect said expansion of said corresponding flange.
